Filed Nov. 27, 1968, Ser. No. 14,688

Term of patent 14 years

Int. Cl. D12—11

U.S. Cl. D90—5

FIG. 1 is a side view of the bicycle chain guard extension, showing my new design;

FIG. 2 is an enlarged side view thereof;

FIG. 3 is a rear view thereof;

FIG. 4 is a top view thereof; and

FIG. 5 is a rear view thereof.

The bicycle and chain guard, partially shown in broken lines of FIG. 1, are included for illustrative purposes only.

I claim:

The ornamental design of a bicycle chain guard extension, substantially as shown and described.
